UNITED STATES PATENT OFFICE.

ALVAH C. ROEBUCK, OF CHICAGO, ILLINOIS, ASSIGNOR TO THE ENTERPRISE OPTICAL MANUFACTURING COMPANY, OF CHICAGO, ILLINOIS, A CORPORATION OF ILLINOIS.

ARC-LAMP MOTOR FEED.

Application filed April 17, 1922. Serial No. 554,281.

My invention relates to feeding mechanism for arc lamps particularly adapted for use in picture projecting machines.

One of the objects of my improvement is to provide simple and efficient motor driving mechanism for automatically feeding the carbons of an arc light such as are used in picture projecting machines, and the like.

A further object is the provision of simple and efficient means for varying the rate of feeding motor actuated arc lamp carbons.

A still further object is the provision of a simple and efficient automatic feeding means for the carbons of an arc light of the character mentioned.

Other objects will appear hereinafter.

An embodiment of my invention is illustrated in the accompanying drawings, forming a part of this specification, and in which—

Fig. 1 is a side view of a fragment of an arc lamp such as used in picture projecting machines equipped with an embodiment of my invention;

Fig. 2 is a section taken on line 2—2 of Fig. 1;

Fig. 3 is a rear elevation of the device of Fig. 1;

Fig. 4 is an enlarged fragmental side view of a portion of the construction looking in the opposite direction to that of Fig. 1; and

Fig. 5 is a fragmental section taken on line 5—5 of Fig. 1.

Referring more particularly to the drawings, I have indicated a framework 10 having upstanding lugs 11 and 12. In the lugs 11 are mounted guide rods 13 upon which a base 14 is slidably mounted. A screw 15 is mounted in lug 12 and threaded in a lug 16 on the base 14 so that rotation of the screw 15 by means of its hand wheel 17, the base 14 will be moved along the guides 13.

On the base 14 is an upright tubular socket 18 in which is rotatably and slidably mounted a post 19. On the top post 19 is a head 20 carrying a yoke 22 which supports the carbon holders, not shown, and their adjusting screw 23. Any desirable form of carbon holders and adjusting devices may be utilized. The parts shown are similar to those described and shown in detail in my co-pending application, Serial No. 554,064, filed April 17, 1922.

The post 19 and head 20 are moved vertically by means of a rod 24 having a notch

25 engaging an extension 26 on the head 20. The rod is slidably mounted in ears 27 on the socket 18 and a spiral gear 28 threaded on the rod 24 meshes with a spiral gear 29 on shaft 30 which is operated by suitable manual means. This mechanism provides means for raising and lowering the carbon holders and their mounting.

The post 19 and head 20 are rotated in the socket 18 by a post 31 attached to the head 20, see Fig. 1. The post 31 engages a peripherally grooved wheel 32 fixed on a shaft 33 and the latter is threaded in a member 34 on the socket 18. The shaft 33 may be operated by a hand wheel 35 so that rotation 70 of said hand wheel causes longitudinal movement of shaft 33 and oscillatory movement of the head 20.

At one end of member 10 is a platform 36 on which is mounted an electric motor 37, or its equivalent. The motor 37 is connected with a shaft 38 by means of a pair of spiral gears 39. The shaft 38 carries a wedge-shaped friction wheel 40 which extends between two friction wheels 41 and 42. The friction wheel 42 is fixed on a shaft 43 which is journaled in a bearing 44 on a frame 45. The frame 45 has an ear 46 threaded on a shaft 47 and the latter is journaled in an ear 48 on said member 45. The member 45 also has a portion 49 mounted in a guide 49 on frame 10. The arrangement is such that upon rotation of screw 47 by means of hand wheel 50 the frame 45 is moved transversely with respect to shaft 38 so as to move shaft 43 toward and away from said shaft 38. The relative movements of the shafts 38 and 43 varies the speed at which shaft 43 will be driven due to sliding the friction gears 41 and 42 on friction wheel 40.

The shaft 43 has a spiral gear 51 fixed on it and the latter meshes with a spiral gear 52 on an upright shaft 53. Between the gear 51 and an adjacent end of a sleeve 54 to which friction wheel 41 is attached, is a compression spring 55. The compression spring tends to press the friction gears 41 and 42 toward each other and toward the driving gear 40. A pin 56 may pass through shaft 43 and notches in collar 54 so as to cause the shaft 43 and sleeve 54 to turn together.

The shaft 53 may have universal joints 57 in it so that when the base 14 is moved toward and away from the motor 37 or when the gears 41 and 42 are moved with

respect to gear 40 the shaft 53 may continue to rotate without binding. At the top of shaft 53 is a spiral gear 58 which meshes with a spiral gear 59 and the latter is rotatably mounted on a shaft 60. Said gear 59 also has clutch teeth 61 which engage clutch teeth of a clutch collar 62. The clutch collar also has teeth 63 which engage the teeth 64 of a gear 65 and the latter is secured to shaft 60. With this arrangement shaft 53 operates shaft 60 through gears 58 and 59, clutch collar 62 and gear 65, and the intermediate clutch teeth.

A gear 68 is mounted on a shaft 69. Said shaft 69 is provided with a hand wheel 70 so that when clutch collar 62 is out of engagement with gear 65 the hand wheel 70 may operate through shaft 69 and gear 68 to rotate gear 65 and shaft 60. This gives quick or rapid speed which is especially useful in returning the carbon holders to their initial starting point for a new trim. For convenience in throwing the motor drive connection into and out of operative condition a lever 71 is pivoted as at 72. The lever 71 carries two pins 73 and 74 with the pin 73 engaging a peripheral groove in clutch collar 62 and pin 74 engaging a peripheral groove in the hub of gear 68. The shaft 69 is provided with a long peripheral groove 75 in the bearing of said shaft 69. A screw 76 is threaded in the bearing and engages the long recess 75 so as to give the shaft 69 a limited amount of longitudinal movement. A spring 77 is placed between gear 59 and collar 62 tending to hold gear 68 out of mesh with gear 65 and holding clutch teeth 63 in engagement with clutch teeth 64. This holds the motor drive mechanism in operative condition. When it is desired to operate the device by hand, hand wheel 70 is pushed in against the influence of spring 77 which brings the gear 68 into mesh with gear 65 and unmashes clutch teeth 63 and 64. It will be apparent that the clutch teeth 61 between gear 59 and clutch collar 62 are sufficiently long to prevent their disengagement when collar 62 is moved as before-mentioned. The collar 62 and gear 59 are both loosely mounted on shaft 60 and the gear 65 fixed on said shaft. Furthermore, a peripheral groove 78 may be formed in the hub of gear 59 with a hook member 79 engaging said peripheral groove for holding the gear 59 in proper relation with gear 58.

The screw 47 has gear teeth 80 formed on one end portion thereof and these gear teeth mesh with a gear 81 which has on one of its faces indications. A pointer 82 is fixed adjacent the gear 81 to cooperate with the indications on the latter. The indications on gear 81 and pointer 82 will indicate the speed at which the carbons are being fed. The rotation of screw 47 will move gears 41 and 42 with respect to gear 40 and this

relation is calibrated on the gear 81 so that the pointer 82 will always indicate the rate at which the carbons are being fed. When he wants the carbons to be fed faster or slower he adjusts the hand wheel 50 in accordance with the indications pointed to by pointer 82.

In operation, the motor 37 may be any desirable means for furnishing power to shaft 38. The gear 49 on shaft 38 rotates the friction gears 41 and 42 at a rate corresponding to the relation between shafts 38 and 43. This adjustment is necessary in order to use carbons of different sizes, varying density, and composition, as well as variations of voltage and amperage in the current supply. As already described, the connection connected with gears 41 and 42 operates the shaft 60 to rotate screw 23 or other feeding means for the carbons. It has also been pointed out above that hand wheel 70 may also be utilized for feeding the carbons to give a hand feed to the latter. The motor actuated connection is also thrown out of and into gear as described above for feeding the carbons either by hand or power.

I claim:—

1. Arc lamp feeding means comprising a carbon feeding screw; a shaft operatively connected with said screw; a motor driven connection having a portion rotatably mounted on said shaft; a clutch collar rotatably mounted on said shaft and in engagement with the motor driven connection; a gear having clutch teeth fixed on said shaft; means for moving said collar into and out of operative relation with said clutch teeth and hand-operated means for driving said gear.

2. Arc lamp feeding means comprising a shaft; a motor driven gear rotatably mounted on said shaft with clutch teeth in said gear; a clutch collar journaled on said shaft and having clutch teeth in both of its ends; clutch teeth fixed on said shaft; and means for moving said collar to engage the clutch teeth on the latter with said clutch teeth fixed on said shaft, the clutch teeth between said collar and said motor driven gear always remaining in engagement.

3. Arc lamp feeding means comprising a shaft; hand operable means connected with said shaft; a member having clutch teeth fixed on said shaft; a clutch collar journaled on said shaft and having clutch teeth on both of its ends; a motor driven member journaled on said shaft and having teeth always in engagement with the clutch teeth at one end of said clutch collar; and a member connected with said collar for moving the latter longitudinally of said shaft to engage and disengage the clutch teeth on one end of said collar and the clutch teeth fixed on said shaft and hand-operated means for driving said first-named member.

4. Arc lamp feeding means comprising a shaft; a gear fixed on said shaft and having clutch teeth thereon; a hand operable gear meshing with the gear on said shaft; a clutch collar journaled on said shaft and having clutch teeth adapted to engage the clutch teeth of the gear fixed on said shaft; a motor driven member journaled on said shaft and having teeth always in engagement with clutch teeth on said clutch collar; and a lever connected with said clutch collar and hand operable gear for moving the clutch teeth on said clutch collar into engagement with the gear on said shaft and moving the hand operable gear out of mesh with said gear on said shaft.

5. Arc lamp feeding means comprising a carbon adjusting member; a shaft connected with said carbon adjusting member; a gear on said shaft having clutch teeth thereon; a motor driven connection; a clutch collar slidably mounted on said shaft and operatively connected with said motor driven connection; a hand driven gear; and a member connected with said clutch collar and hand driven gear adapted to move the clutch collar out of engagement with said clutch teeth and at the same time move the hand driven gear in meshing relation with the first-mentioned gear.

6. Arc lamp feeding means comprising a carbon adjusting member; a shaft operatively connected with said carbon adjusting member; a clutch collar splined on said shaft; a motor driven connection operatively connected with said clutch collar; clutch teeth fixed on said shaft; a hand operable

shaft; said hand operable shaft being mounted for longitudinal movement; a connection between said hand operable shaft and said clutch collar; and teeth fixed on said first-mentioned shaft whereby movement of the hand operable shaft in one direction disengages the clutch collar from said clutch teeth on the first-mentioned shaft and effects an operative connection between said clutch teeth and said hand operable shaft.

7. Arc lamp feeding means comprising a carbon adjusting member; a shaft operatively connected with said carbon adjusting member; a gear journaled on said shaft and held against longitudinal movement; a motor driven connection connected with said gear; a collar mounted on said shaft and having a clutch tooth connection with said gear; a spring tending to move the clutch collar away from said gear; a gear fixed on said shaft and having clutch teeth thereon adapted to engage the clutch collar; a hand operable shaft mounted for longitudinal movement; a gear fixed on said hand operable shaft; and a lever having a connection with said gear and the hand operable shaft and said clutch collar adapted to move the latter to engage and disengage the teeth on said gear with said clutch collar and move the gear on said hand operable shaft into and out of operative relation with the gear fixed on the first-mentioned shaft.

In testimony whereof I have signed my name to this specification on this 13th day of April, A. D. 1922.

ALVAH C. ROEBUCK.
